UNITED STATES PATENT OFFICE.

BERNARD MESTEKIN, OF WASHINGTON, DISTRICT OF COLUMBIA.

LINK FOR CHAIN BRACELETS AND DETACHABLE HINGES FOR THE SAME.

Application filed June 27, 1922. Serial No. 571,317.

To all whom it may concern:

Be it known that I, BERNARD MESTEKIN, a citizen of the United States of America, and a resident of Washington, District of Columbia, have invented a new and useful Improvement in Links for Chain Bracelets and Detachable Hinges for the Same, of which the following is a specification.

When carrying bracelets in stock a large number is required to meet all the demands as to size. To a great extent this may be avoided in the so-called chain bracelet by preparing detachable links ready for assembly to build up a bracelet of any desired size. One object of my invention is to make such a detachable bracelet link. Another object of my invention is to provide a bracelet link with a detachable hinge of strong and durable construction without sacrificing the beauty of the assembled bracelet. Another object of my invention is to make such a hinge not only easy and quick for assembly but to also provide means for detaching any link without the intervention of a skilled mechanic. Another object of the invention is to make a bracelet link and a hinge therefor in such a manner as to build up a chain bracelet without the necessity of swaging the hinge pivots.

30 In the drawing which forms a part of my specification—

Figure 1 shows a perspective view of several links connected.

Figure 2 is a top view of an individual link.

Figure 3 is a side elevation of a link.

Figure 4 is an enlarged sectional view taken on plane 4—4 in Figure 2.

Figure 5 is an enlarged sectional view 40 taken on plane 5—5 of Figure 2.

Figure 6 is a detail of the hinge pin with a fraction of the link to which the pin is soldered.

Figure 7 shows a modified form of link.

45 Figure 8 shows a side and end views of one form of hinge pin used in connection with my modified link.

Figure 9 shows the socket end view of a link.

50 Figure 10 shows a side and end view of another form of hinge pin used with my modified link.

Fig. 11 is a sectional view taken on a plane along the axis of the hinge.

55 Referring in detail to the drawing: 1 represents a link made up of walls of any de-

sirable thickness and from any metal such as silver, gold or platinum having a provision generally indicated 2 for a gem or gems on the top wall. The bottom wall, 60 three (3) being left open and the edges made smooth since the said edges come into contact with the skin.

In the form shown in Figures 2, 3 and 5, each link is provided with a hinge pin, 4, at 65 one of the end faces and a socket, 5, at the opposite end face. The end faces are beveled off from midway toward the lower face of the link as shown at 6, so as to permit the assembled bracelet to flex into an annulus. 70 The hinge pin is best shown in Figure 6. It consists of a piece of half round rod bent into U shape with the flat faces of the half round rod facing each other as clearly shown in the drawing. The arm 11, of the hinge 75 pin differs from the companion arm 12, in that it has a shoulder, 9 at the free end thereof. The arm 12 is permanently attached to the end face of the link by soldering or it may be made integral with the end face. 80 The webb 8, of the U-shaped hinge pin is slightly springy even after it has been heated, so that the tendency for the two arms 11 and 12 is to stay slightly spread apart as shown in Figure 6. 85

The socket is formed by soldering on the inside of the end face, of the link, a piece of tubing, 14, with a portion cut away along a chord. The inner diameter of the tubing being slightly larger than the diameter of 90 the pin 4. Of the two faces 16 and 17 one face is formed with a socket opening as shown at 18 (Figure 9) the opposite face being left closed. The socket opening 18, is formed in sliding fit with the hinge pin 95 so that there is formed a retaining shoulder 15 which cooperates with the shoulder 9 on the hinge pin. A small hole, 20, is also provided in the socket tubing as seen in Figure 4. When assembling one link to another the 100 two links are placed so that the end 8 of the hinge registers with the socket opening 18 of the other link. The pin is then slid endwise into the socket the prong 11 approaching 12 until the shoulder 9 reaches beneath 105 the inside of side face 16 when it snaps out due to the slight springiness of the web 8, the parts assuming the relative positions illustrated in Fig. 11 and thus forming a safe and strong catch. 110

When it is desired to disassemble a link a pointed but not sharp implement is forced

into the hole 20 with a slight pressure to force the prong 11 slightly to unlatch the shoulder 9 from 15 and while under this pressure the links are readily separated.

5 In my modified form shown in Figure 7, each link is provided with two identical sockets one on each end face. The hinge pin has the general appearance of an 8, as seen at 10^A and 10^B and when assembling, 10 one half of the pin enters into one socket while the other half into the socket of the adjacent link. In disassembling a similar pointed tool can be used for one or the other of the prongs 11^A or 11^B as I provide each of 15 the socket tubes with a hole 20.

The pins shown at Figures 8 and 10 differ by a slight change and one or the other may be used for mere mechanical convenience.

20 I claim:

1. A chain link for a bracelet comprising a socket adapted to receive a hinge pin, a split hinge pin to fit said socket, said socket being contained in the end face of the link, 25 a longitudinal slot in the face of the link communicating with said socket and complementary detents on the hinge pin and socket.

2. A hinge pin for a chain link bracelet having prongs to slidably fit a socket, and retaining shoulders on said prongs to lock 30 the pin in the socket.

3. A hinge pin for chain link bracelets having two prongs and a middle body, said prongs being yieldingly held at a space from 35 the said middle body, and locking shoulders on said prongs.

4. A chain for a bracelet having a socket along its end face, a longitudinal slot com-

municating with said socket, a perforation in the wall of said socket opposite the slot 40 and a pin retaining shoulder in said socket.

5. A chain link for a bracelet having a longitudinal slot in its end face, a socket communicating with said slot, a retaining shoulder at one end of said socket and a hole 45 in the wall of said socket opposite the slot and near the retaining shoulder, a yielding split hinge pin to fit into said socket and to be retained by said shoulder.

6. A chain link for a bracelet having a socket adjacent its end face, a longitudinal slot communicating with said socket through the end face, a retaining shoulder in said socket, a hinge pin to disconnectedly fit into 50 said socket and means permitting the removal of said hinge pin.

7. A chain link for a bracelet having a socket adjacent its end face, a longitudinal slot communicating through the end face to the socket, a retaining shoulder in said socket, a split pin to disconnectedly enter 60 said socket, a shoulder on said pin to co-operate with the shoulder in the socket and means facilitating the disconnection of said pin from the socket.

8. A chain link for a bracelet and hinge thereof comprising a box like body and a hinge socket at the end face thereof, a split hinge pin and detachable locking means between the socket and pin.

9. A hinge for two bracelet links to be hinged side by side, comprising a socket communicating with a face of a link and a split hinge adapted to be detachably locked 70 in said socket.

BERNARD MESTEKIN.
